UNITED STATES PATENT OFFICE.

WILLIAM J. MULVANEY, OF LISLE, ILLINOIS.

AUTOMATIC STOVE-LIGHTER.

1,299,376.

Specification of Letters Patent. Patented Apr. 1, 1919.

Application filed October 20, 1917. Serial No. 197,659.

To all whom it may concern:

Be it known that I, WILLIAM J. MULVANEY, a citizen of the United States, residing at Lisle, in the county of DuPage and State of Illinois, have invented new and useful Improvements in Automatic Stove-Lighters, of which the following is a specification.

This invention relates to new and useful improvements in automatic lighting devices, and the principal object of the invention is to provide means for relighting a stove if the same should become extinguished through accident.

Another object of the invention is to provide an electric circuit combined with a thermostat which will automatically complete the circuit and relight the wick, when the same is extinguished.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a front view of a stove equipped with my improvement.

Fig. 2 is a detail view showing the arrangement of parts adjacent the wick.

Fig. 3 is a detail view showing the arrangement of rheostat and contacts.

Fig. 4 is a plan view.

In these figures 1 indicates the stove, 2 the oil tank thereof and 3 the burner. 4 represents a perforated plate forming a top for the stove and supported by the rods 5 which have their lower ends connected with the tank. 6 indicates an insulating member of glass or the like carried by the stove and adapted to support any suitable form of spark plug with its contacts adjacent the

wick so that when a spark takes place the wick will be lighted thereby. The plate 4 carries any suitable form of thermostat 8 which is insulated from the top by the insulated strip 9 and said thermostat has secured thereto a cap 10 movable with the thermostat and forming an electric contact, said cap being connected to the battery 7. The thermostat may be composed of the well known form of wafers suitably connected together so that when subjected to heat said wafers will expand and bulge outwardly and thus lift the cap from off the plate 4. Said thermostat is supported on the insulated strip 9 so as to be out of electrical contact with the plate. When the thermostat closes the circuit through the primary coil of box 7 a current is induced in the secondary coil, which is connected with the spark plug so that a spark is produced at said plug. It will thus be seen that when the stove is lighted the heat thereof will cause the thermostat to expand so as to raise the cap out of contact with the plate and thus break the electric circuit. If the lamp should become extinguished the thermostat will contract thus permitting the cap to come in contact with the plate so as to complete the circuit and cause a spark at the plug, thereby lighting the wick again.

It is thought from the foregoing description that the advantages and novel features of my invention will be readily apparent.

I desire it to be understood that I may make slight changes in the construction and in the combination and arrangement of the several parts, provided that such changes fall within the scope of the appended claim.

What I claim is:—

An automatic lighter for stoves comprising a perforated plate connected with the top of the stove, a thermostat on the plate and insulated therefrom, a cap connected with the thermostat and having its edges contacting with the plate in the contracted position of the thermostat, a spark plug adjacent the wick and electric means controlled by the thermostat for causing a spark at the plug.

In testimony whereof I affix my signature.

WILLIAM J. MULVANEY.
